VENTILATION CONDUIT FOR A WATER CLOSET

Clyde J. Hunnicutt, Jr., 3026 E. Garfield St.,
Phoenix, Ariz. 85008

Filed Oct. 2, 1972, Ser. No. 293,808

Term of patent 14 years

Int. Cl. D23—02

U.S. Cl. D23—71

FIG. 1

FIG. 2

FIG. 1 is a perspective view taken from the front, top and left side of a ventilation conduit for a water closet showing my new design; and

FIG. 2 is a perspective view taken from the rear, top and right side thereof.

I claim:

The ornamental design for a ventilation conduit for a water closet, as shown.
